UNITED STATES PATENT OFFICE.

JOSEPH KUGEL, OF CINCINNATI, OHIO.

GLASS-CLEANER.

1,142,716.

Specification of Letters Patent. Patented June 8, 1915.

Application filed July 6, 1914. Serial No. 849,328.

To all whom it may concern:

Be it known that I, JOSEPH KUGEL, a citizen of the United States, residing at the city of Cincinnati, in the county of Hamilton and State of Ohio, have invented certain new and useful Improvements in Glass-Cleaners, of which the following is a specification.

The object of my invention is to produce a cheap, simple and highly efficient device for cleaning glasses, tumblers, cups and the like which are used for drinking liquids at restaurants, cafés, soda fountains and drinking places of all kinds.

In the ordinary process of cleaning glasses by hand, thorough work cannot be done, thus fatty and sticky substances from milk and syrups, residues and coatings from liquids of all kinds such as from beer, ale, drugs and the like are left on the inside of the glass; the glass on the inside is often left slimy and viscous, rendering the drink unpalatable, unhealthy and unsanitary, inviting sickness and disease. It can readily be applied behind bars, stands, on basins and sinks or any place where it is desired or customary to wash the glasses.

In the accompanying drawing forming part of this specification, Figure (1) is a side elevation of the device, partly broken away to illustrate construction, and Fig. (2) is a sectional view of the device.

The device can be connected and supported in any desirable manner, in the present instance it is supported on a bracket (1) which can be fastened at any convenient point convenient for the operation of the device.

In carrying out my invention I use the ordinary or a special water pipe (2), which can be cut in at any place along its extent, and at its end (3) the pipe (2) is closed. At this end I extend the water communication through medium of a smaller spray pipe (4), which fits, at its inner end, into the main pipe 2. Over the pipe (4) I slip a sleeve (5) carrying at its inner end a pinion 6. The outer end of pipe (4) is screw threaded at (7) onto which screw thread is screwed a nut (8) which holds the pipe (4) and the sleeve and pinion in a fixed and normal position. The sleeve (5) is slightly tapered as shown and onto this tapered sleeve (5) I secure the circular or annular brush (9), through the agency of its tapered sleeve (10) fitting onto the

tapered sleeve (5). Onto the end (3) of the pipe (2), that is, at the end of the main pipe, where the spray pipe (4) meets said pipe, and forms the center, I connect, in any desired manner, a hood (12), in the present instance flared, but it may be of any shape desired. In the pipe (2), at a convenient point I place a plug or key valve (14) onto which I fasten a lever handle (15) at point (16) held to the valve at one of its ends by a nut connection (16'). This valve may be of any approved form or construction, usually used in water pipes of this character. To the lower end of the lever handle (15) I pivotally connect, at pivot point (17), a rod (18) carrying at its outer end a rack (19) which meshes with the teeth of pinion (6) which revolves the sleeve (5) and consequently the brush (9) in the glass (20). Moving the handle lever (15) forward and backward opens or closes the valve (14) and opens or closes water communication to the glass (20) to be washed, which has been placed in the hood (12). In Fig. (1) the valve is closed and in Fig. (2) it is open, the arrows showing the path of the water.

In operation, the glass (20) is placed in the hood (12) as shown in Fig. (2), the handle lever (15) being pulled forward to position shown in dotted lines in Fig. (1), turning the plug or key valve (14) to a position shown in Fig. (2), establishing water communication, the water rushing through pipes (2) and (4) and striking with force against bottom of glass (20) becoming diffused all over the glass at the bottom; at the same time the handle lever (15) is pulled forward the rack arm (18) is pushed forward thus revolving the brush (9); this repeated action of pulling the handle lever (15) forward and backward keeps pumping the water into the glass (20) and keeps revolving the brush (9), thus thoroughly washing, brushing and rinsing the glass, the water running out toward the open end of the glass and finally running into the drip pan or waste sink. The glass can be moved in and out as the brush is revolving and the water is being sprayed, if desired. The water comes in with great force and the brush revolving at the same time, thorough cleaning of the glass is the result, all the coating, fatty substances and sticky matter being removed, the glass is thus rendered clean and sanitary.

A coiled spring 21 on the hub of the valve is used, if desired, to pull the handle lever 15 back into normal closed position, if it is not done by the operator. Any form of spring as now commonly used for purposes of this kind may be employed.

It is evident that the hood 12 need not be used by me as the brush and water will clean the glass, the hood being used to keep the water from splashing and confining it.

The operation is very quick and glasses of various sizes can be cleaned.

The device can be made of any material and its various parts of any shape or contour. The brush when worn can readily be replaced.

It will readily be obvious that this device can be placed at any point where it is necessary to clean glasses and similar articles.

While I have described one specific form and construction of my glass cleaner, it will readily become apparent that the same is capable of many changes and modifications, without departure from the principle of the invention, and I wish to be understood as not limiting myself to the specific construction herein shown and described, but that said modifications still fall within the scope of my invention.

What I claim as new and my invention and desire to secure by Letters Patent is:

1. In a device for cleaning glasses of the character described, a water pipe, a

brush, said brush surrounding said water pipe, a valve in the water pipe and a handle thereon, and actuating connections from the handle to the brush, whereby the turning of the handle operates to open and close the valve and revolve and stop the brush simultaneously to clean the glass.

2. In a device for cleaning glasses of the character described, a water pipe, a brush, a hood, said water pipe and brush extending into said hood, said brush surrounding said water pipe, a valve in the water pipe and a handle thereon, and actuating connections from the handle to the brush whereby the turning of the handle operates to open and close the valve and revolve and stop the brush simultaneously to clean the glass.

3. In a device for cleaning glasses of the character described, a water pipe, said water pipe having an extension at approximately right angles thereto, a sleeve, said sleeve covering said extension, a brush attached to said sleeve, a valve in said water pipe, having a handle and means connecting said handle and sleeve, for opening and closing the valve and revolving and stopping the brush so as to clean the glass.

In testimony whereof I affix my signature in presence of two witnesses.

JOSEPH KUGEL.
